ROBERT GIDLEY, OF LAGRANGE, NEW YORK.

Letters Patent No. 72,477, dated December 24, 1867.

IMPROVEMENT IN GATES.

The Schedule referred to in these Letters Patent and making part of the same.

TO ALL WHOM IT MAY CONCERN:

Be it known that I, ROBERT GIDLEY, of Lagrange, in the county of Dutchess, and State of New York, have invented a new and improved Folding Gate; and I do hereby declare that the following is a full, clear, and exact description thereof, which will enable others skilled in the art to make and use the same, reference being had to the accompanying drawings, forming part of this specification, in which—

Figure 1 represents a side elevation, partly in section, of my improved gate.

Figure 2 is a transverse sectional elevation of the same, the plane of section being indicated by the line $z z$, fig. 1.

Similar letters of reference indicate corresponding parts.

This invention relates to a new folding gate, which can be easily opened or closed by persons in a carriage or on horseback. It consists of a picket-gate pivoted to a bar, which is suspended in a post, so that when the said bar is swung back, by means of suitable levers, the gate will also be swung back with the bar. The gate will be self-closing, unless it is held open by suitable stops.

A B are the posts, between which the gate is to be arranged. They are connected by a suitable sill, C, upon which a rail, a , may be arranged. The post B is slotted, as shown in fig. 2, and is considerably higher than the gate is to be. D D are two posts, arranged in a line with the post B, which line is at right angles to the sill C. E is the gate. The same consists of two or more horizontal bars $b b$, to which a series of vertical pickets, $c c$, is pivoted. The inner ends of the bars $b b$ are pivoted, by means of pins d , in the post B, as is clearly shown in the drawing. The outer end of each bar b carries a small roller, e . The roller on the lower bar b fits upon the rail a while the gate is closed, as in fig. 1. G is a horizontal shaft, having its bearings in the upper parts of the posts D D, and, perhaps, also in the post B, as shown. On the end of the shaft G are formed cranks $f f'$ respectively, as shown in fig. 1. In the centre of the shaft G, the same is provided with a crank, g , which has a hook or slot on its lower end fitting around a pin, h , that projects from the bar F. When the gate is closed, the cranks $f f'$ are in a horizontal position, or nearly so, as shown in fig. 1. When the gate is to be opened, one of the cranks f or f' is swung down into the position shown by red lines in fig. 1. Thereby the shaft G is turned, and the crank g , that was in a vertical position, is brought about into a horizontal position, carrying the bar F along, as is indicated by red lines in fig. 1. By the motion of the bar F the bars b of the gate are moved back through the slot in the gate, and then up, so that the gate comes into the position which is shown by red lines in fig. 1. In this position the wheel l , on the upper bar b of the gate, runs on the rail a . To keep the gate open, it is only necessary to move an oscillating bar, H, which is hinged to the side of the post D, over the end of one of the cranks $f f'$, as shown by red lines in fig. 1. On each post D is such a bar H, and both bars H are connected by means of a rod, i , as shown, so that, when the bar H on one post is used to lock the gate, the bar H on the other post may be employed to disengage the crank f or f' locked. The gate will then, when the cranks $f f'$ are both released, fall closed by its own gravity.

Having thus described my invention, what I claim as new, and desire to secure by Letters Patent, is—

1. A self-closing gate, when arranged so that it is brought through the slotted post B, and into an inclined position, when opened, substantially as herein shown and described.
2. The gate E, when consisting of horizontal bars $b b$, pivoted to pickets $c c$, and when pivoted to a suspended bar F, in combination with the shaft G, having the crank g and the handles $f f'$, all made and operating substantially as herein shown and described.
3. The above, in combination with the locking-levers H H, connected by a rod, i , substantially as herein shown and described.
